UNITED STATES PATENT OFFICE.

AUGUST P. PALMQUIST, OF GALESBURG, ILLINOIS.

DESIGN FOR A WASHBENCH.

54,117.

Specification for Design.

Patented Nov. 4, 1919.

Application filed April 23, 1919. Serial No. 292,179. Term of patent 14 years.

To all whom it may concern:

Be it known that I, AUGUST P. PALMQUIST, a citizen of the United States, residing at Galesburg, in the county of Knox and State of Illinois, have invented a new, original, and ornamental Design for Washbenches, of which the following is a specification, reference being had to the accompanying drawing, forming a part thereof.

In the drawing:

The figure is a perspective view of a wash bench showing my new design.

I claim:

The ornamental design for a washbench, substantially as shown.

In testimony whereof, I affix my signature.

AUGUST P. PALMQUIST.
